CLAIM

The ornamental design for a display screen with graphical user interface for visualization of gaming device network as shown and described.

DESCRIPTION

FIG. 1 is a view of a display screen with a graphical user interface (GUI) for visualization of a gaming device network showing an embodiment of the design;

FIG. 2 is a view of the display screen with the GUI showing an alternate embodiment of the design;

FIG. 3 is a view of the display screen with the GUI showing an alternate embodiment of the design; and,

FIG. 4 is a view of the display screen with the GUI showing an alternate embodiment of the design.

Dashed (broken) lines represent structure or features that form no part of the claimed design.

1 Claim, 4 Drawing Sheets
